EDGAR E. GREVE, OF BELLEVUE, PENNSYLVANIA, ASSIGNOR, BY MESNE ASSIGNMENTS,
TO OIL WELL SUPPLY COMPANY, OF PITTSBURGH, PENNSYLVANIA, A CORPORATION
OF NEW JERSEY

METHOD OF AND APPARATUS FOR AUTOMATICALLY RAISING LIQUIDS FROM WELLS

Application filed December 17, 1927. Serial No. 240,806.

My invention relates to a new and improved method of and apparatus for automatically raising or ejecting liquids from wells, and more particularly to the art or method and system of pumping oil wells.

My invention contemplates the introduction of an actuating fluid under pressure into the liquid in a well, and utilizing the said fluid for raising the liquid or, more specifically, a column of oil. The said pressure fluid is introduced at several levels in the well and is under automatic control, whereby a continuous flow of oil may be effected.

One of the prime objects of the present invention is to provide automatically operable means for effecting an elevation of and the discharge of liquids from a well, said means being located at different levels of the well, whereby, after starting the flow of liquid in the well, the flow will be continuous from the bottom to the top of the well, notwithstanding the depth of the well. Another object of the invention is to provide automatically operable means that will function regardless of the percentage of submergence to the lift.

Other objects are to provide means whereby different levels of oil may be worked automatically or in stages; a method of pumping that may be employed without producing back-pressure on the producing sands; to provide for a positive control of the actuating fluid and the utilization of the same fluid pressure for the pumping operation; and to provide a method of and means for effectively elevating the oil through a well of very great depth, irrespective of the percentage relation of submergence to lift.

In the accompanying drawings, which illustrate an application of my invention:

Fig. 1 is a longitudinal sectional view, showing a portion of the apparatus embodying my invention disposed in a well casing or tubing;

Fig. 2, a view similar to Fig. 1, showing another portion of the apparatus designed to be disposed in the casing at a lower level;

Fig. 3, a part longitudinal section and a part elevational view of a modified form of that portion of the apparatus shown by Fig.

1, the said portion being shown located in a well casing;

Fig. 4, a diagrammatic view illustrating an oil well, oil well casing, and my improved apparatus located in the well casing;

Fig. 5, a horizontal sectional view taken on line V—V of Fig. 1;

Fig. 6, a similar view, the section being taken on line VI—VI of Fig. 3; and

Figs. 7 and 8, sectional views, respectively taken on line VII—VII of Fig. 1 and line VIII—VIII of Fig. 3.

Referring to the drawings, 5 designates a well casing or tubing through which the oil or other liquid is raised, and 6 the tubing or pipe for conveying the operating pressure fluid from a source of supply at the top of the well to the points of use in the well. Arranged at desired points in the tubing 6, I provide a number of valve bodies or chambers 7, and a valve body or chamber 8, the latter being located below the lowermost valve chamber 7, and being in open communication with the latter by a section *a* of the actuating fluid tubing 6.

Disposed below valve chamber 8, and designed to be connected with tubing 6 by a perforated pipe section 9, I employ a packer structure 10, said structure being preferably of the hook-wall type of packer. This packer has connected at its lower end a valve cage 11 carrying a check valve 12.

It will be understood that the packer may be positioned at or near the bottom of the casing or at any desired elevation therein, and that it may be let into the casing and set by the string of tubing 6. The packer per se is of well known construction, familiar to those skilled in this art, and it is believed a detailed description of the packer is unnecessary.

Referring now to the valve body 7 and, first, to the form of Fig. 1, this body is formed with an enlarged fluid passage 13 extending longitudinally throughout the length of the body 7, and with a piston valve receiving annular passage 14.

Passage 14 is designed to receive a balanced piston or compound valve structure, designated generally by the numeral 15. As illus-

- trated, this balanced piston valve includes a hollow body portion 16 having ports 17 and 18. Extending upwardly from the hollow body portion is a stem 19, said stem carrying at its upper end a nut 20, packing 21, a spring 22 interposed between an annular shoulder 23 formed in the body, and a head 24 carried by the stem. In addition to the parts mentioned, stems 19 is surrounded by a packing 26 and a gland nut 25 cooperating therewith.
- 27 designates a valve seat located in the hollow piston valve body, said seat 27 being designed to carry a ball valve 28, and is of a construction to provide means for connecting the two parts constituting the hollow body 16.
- 15 Valve 28 is designed to control the passage of the actuating fluid up through the hollow piston valve, and prevent the entrance of liquid to the actuating fluid container or pipe 6, as will be hereinafter described.
- 20 Packing means 29 are disposed in the hollow piston valve body above the ports 18. The lower end of the hollow piston is closed by a depending member 30. Member 30 has mounted thereon packing 31 and a nut 32.
- 25 Formed in the wall of the piston receiving passage are ports 33, the latter being designed to cooperate with the ports 18 of the piston when the latter is in a lowered position.
- 30 In addition to the ports 33, the body of the valve device is provided with ports 34 designed to cooperate with the ports 17 formed in the hollow piston valve. In the position of the parts shown by Fig. 1, it will be seen that
- 35 the ports 17 are in register with the ports 34, and that the ports 18 of the piston valve are out of register with the ports 33 formed in the wall of the piston-receiving passage. In this position of the valve structure, it will be understood that the actuating fluid is prevented from entering the piston valve and passing to the column of oil or liquid in the casing.
- 40 As above stated, in connection with the lowermost piston valve body 7, I employ a valve body or chamber 8. Said chamber or body 8 is formed with an enlarged passageway 35 and a valve receiving passageway 36. 37 designates a port designed to permit the passage of the actuating fluid from the chamber 8 into the column of oil or other liquid in the casing, and 38 designates a port forming communication between the passage 35 and the valve receiving passage 36. 39 is a check valve mounted in the valve receiving passage 36 on a seat 40 carried therein, the upper end of passage 36 being closed by a plug 41.
- 45 By reference to Fig. 4, it will be noted that the apparatus embodying my invention may be positioned in the well, or in the well casing, by lowering the actuating fluid conductor tubing together with the valve mechanisms and the packer structure as a unit.
- 50 The number of balanced piston valves to be employed in the string of tubing will, of course, depend upon the depth of the well.

In operation, it will be understood that when starting the apparatus, the air or other fluid under pressure that is supplied to the fluid conducting tubing 6 will travel downwardly through said tubing until it reaches the lower valve chamber 8, the latter being submerged in the liquid to be elevated, owing to the fact that the piston valves in the respective chambers or bodies 7 are now closed or in the position shown by Fig. 1, thereby preventing the passage of actuating fluid into the liquid to be raised, prior to the travel of the actuating fluid down to the lower end of the actuating fluid conductor 6, or to the said valve chamber 8. The fluid under pressure delivered to chamber 8 will force valve 39 upwardly and pass through the ports in said valve structure 8 and into the column of oil in the casing. Upon the lifting of the valve 39, there is a back pressure created which will close the packer foot valve 12, and this action will prevent any back pressure reaching the producing sand.

Assuming that the oil or other liquid to be pumped has been elevated through the check valve 12, the hollow packer structure, and the perforated pipe 9, by the escape of the actuating fluid through valve chamber 8, up to and above the level of valve 28 of the piston valve, the weight of the liquid acting on the balanced piston valve places this valve out of balance, causing it to travel downwardly, registering its ports 18 with the ports 33 of the body 7.

When in this position, the actuating fluid will pass from passage 6 into the hollow piston valve, raising ball valve 28 from its seat and passing into the column of oil or other liquid through the ports 17 and 34, and raising the liquid in the casing above the next higher stage or valve body 7. This action is repeated by the next higher automatically operating mechanism, until the liquid is elevated to the point desired.

It will be seen that the rising column of liquid is utilized for effecting an operation of the balanced piston valves for the purpose of admitting the actuating fluid to the liquid and that the volume of pressure actuating fluid admitted at any particular level may be controlled by the balanced piston valve at that particular level.

In the form of Fig. 3, I have shown a modified construction of the balanced piston valve mechanism incorporated in the valve chamber or body 7a, as well as a different valve construction in the valve body 8a. The only substantial difference, however, between the form of Fig. 1 and this modified form, is in the number of valves employed and their co-operating parts. Thus, in place of a single balanced piston valve receiving passage, as in the form of Fig. 1, I have provided four smaller valves and passages. The same reference characters employed on Fig. 1 have

been retained, with the exception that the letter *a* has been added to each character.

I claim:

1. An apparatus for elevating liquids from a well including an actuating fluid pressure pipe having outlet openings arranged at different vertical levels therein, automatically operable balanced piston valves for controlling the discharge of actuating fluid from said pipe, said valves being actuated by the height of the column of the liquid in the well, and means for preventing the liquid being raised from entering the pressure fluid supply pipe.
- 15 2. An apparatus for elevating liquids from a well including an actuating fluid pressure pipe having outlet openings arranged at different vertical levels therein, automatically operable balanced piston valves for controlling the discharge of actuating fluid from said pipe, said valves being actuated by the height of the column of the liquid in the well, and means for preventing the liquid being raised from entering the pressure fluid supply pipe, said means including a ball valve and packing carried by the piston valve.
- 20 3. An apparatus for elevating liquid from a well including an actuating fluid supply pipe disposed in the well casing having a series of valve-controlled openings located in different horizontal planes, piston valves for controlling the said openings, a float valve chamber located in the supply pipe below the lowermost piston valve, a perforated pipe section depending from the said float valve chamber, a hollow packer structure carried by the said pipe section, and a foot valve below the packer.
- 25 4. An apparatus for elevating liquids from a well including an actuating fluid supply pipe disposed in the well casing having a series of valve controlled openings located in different horizontal planes, balanced piston valves for controlling the said openings, and means connected with the lower end of the fluid supply pipe including a check valve for preventing back pressure from the said supply pipe entering the oil producing sand.
- 30 5. An apparatus for elevating liquids from a well including an actuating fluid pressure pipe having outlet openings arranged at different vertical levels therein, automatically operable balanced piston valves for controlling the discharge of actuating fluid from said pipe, said valves being actuated by the height of the column of liquid in the well, a float valve chamber in the supply pipe disposed below the lowermost piston valve, and a float valve therein.
- 35 6. The method of pumping wells which consists in first discharging fluid under pressure into the column of liquid in the well at a low level in the column of liquid to raise the liquid level in the well, and then discharging fluid under pressure into the column of

liquid in the well at a higher level in the column of liquid while continuing to discharge fluid under pressure in the column of liquid in the well at said lower level.

7. Apparatus for elevating liquid from a well comprising an actuating fluid supply pipe having outlet openings arranged at different vertical levels therein, and valves for controlling the discharge of actuating fluid from the pipe through said openings into the column of liquid, each valve being automatically actuated by submergence below the top of the column of liquid in the well to open and remain open so long as such valve is submerged to at least a predetermined depth.

8. Apparatus for elevating liquid from a well comprising an actuating fluid supply pipe having outlet openings arranged at different vertical levels therein, and valves for controlling the discharge of actuating fluid from the pipe through said openings into the column of liquid, each valve being automatically actuated by submergence below the top of the column of liquid in the well to open and remain open so long as such valve is submerged to at least a predetermined depth, each valve being balanced to remain in the position assumed thereby irrespective of changes in the actuating fluid pressure.

9. The method of pumping wells which consists in raising the liquid level in the well by introducing fluid under pressure into the column of liquid in the well at a low level in the column of liquid, and then introducing fluid under pressure into the column of liquid at one or more higher level or levels while continuing to introduce fluid under pressure into the column of liquid at said lower level, thus producing continuous flow of liquid upwardly in the well.

10. The method of pumping wells which consists in introducing fluid under pressure into the column of liquid in the well at a low level to raise the liquid level in the well, and then introducing fluid under pressure into the column of liquid both at said lower level and at a higher level, and then introducing fluid under pressure into the column of liquid simultaneously at said lower level and at a plurality of higher levels.

11. Apparatus for elevating liquids from a well including an actuating fluid supply pipe having outlet openings arranged at different levels to introduce actuating fluid into different portions of a column of liquid, and valves for automatically controlling discharge of actuating fluid from said pipe through said openings into the column of liquid, said valves being responsive to the depth of submergence and being balanced to remain in the position assumed thereby irrespective of changes in the actuating fluid pressure.

12. Apparatus for elevating liquids from a well including an actuating fluid supply pipe having outlet openings arranged at different levels to introduce actuating fluid into different portions of a column of liquid, and valves for controlling discharge of actuating fluid from said pipe through said openings into the column of liquid, each valve being automatically actuated to open position by being submerged by the rising column of liquid in the well.

13. Apparatus for elevating liquids from a well including an actuating fluid supply pipe having outlet openings arranged at different levels to introduce actuating fluid into different portions of a column of liquid, and valves for controlling discharge of actuating fluid from said pipe through said openings into the column of liquid, each valve being automatically responsive to the depth to which it is submerged by the rising column of liquid in the well to open and remain open so long as the same is submerged to at least a predetermined depth.

25 In testimony whereof I affix my signature.
EDGAR E. GREVE.
